UNITED STATES PATENT OFFICE.

CHARLES L. HALSTEAD, OF LA CROSSE, WISCONSIN.

DEVICE FOR SECURING HOSE-BANDS.

SPECIFICATION forming part of Letters Patent No. 436,706, dated September 16, 1890.

Application filed July 30, 1890. Serial No. 360,409. (No model.)

To all whom it may concern:

Be it known that I, CHARLES L. HALSTEAD, a citizen of the United States, residing at La Crosse, in the county of La Crosse and State of Wisconsin, have invented certain new and useful Improvements in Devices for Securing Hose-Bands, &c.; and I do hereby declare the following to be a full, clear, and exact description of the invention, such as will enable others skilled in the art to which it appertains to make and use the same.

My invention relates to an improvement in hose-bands and a device for attaching them to the hose.

15 The objects of my invention are: First, a band or strap for securing hose to couplings, nozzles, &c.; second, a device for applying the same around the hose, so that it shall be drawn so tight that the hose will be closely 20 compressed against the coupling, thereby preventing leakage and rigidly fastening the same together. I attain said object by a certain combination, construction, and arrangement of parts, fully described in this specification, and illustrated in the accompanying drawings, in which—

Figure 1 is a perspective view of said device. Fig. 2 is an end view illustrating the same when in use. Fig. 3 is a view of the 30 hose-band specially adapted to my device. Fig. 4 is a view of a piece of hose with the band fastened around the same.

My invention comprises two bent levers A and B, pivoted together at G, so that by 35 pressing the handles a and b the jaws a' and b' of my device are opened. The jaw a' is shorter than the jaw b' and has a flange a'', for the purpose of engaging the cross-bar portion d of the band D. The jaw b' is 40 constructed with the slots b'' in the end of the same, which are adapted to receive and hold the ends d'' of the hose-band D. Upon the top of the jaw b' there is pivoted the wedge

E, which is forced in between the ends d'' of the hose-band with a view of securely holding 45 the same and preventing them from pulling through the slots b'' when the device is in operation. Between said levers there is located a spiral spring F, which closes the jaws of the device.

50 The hose-band D is constructed, as shown in Fig. 3, with the cross-bar d and the ends d'' curved outwardly and bent around to such an extent as to form a ring.

In applying the band D the ends are placed 55 through the cross-bar d, as shown in Fig. 2, and the band is then adjusted to the hose at the point to be secured. The device is then applied (see Fig. 2) and the handles are compressed together, which tightly draws the 60 band around the hose, after which the ends of the band are bent down, as shown in Fig. 4.

What I claim is—

1. In a device for applying hose bands or wires, the combination of two levers pivoted 65 to each other, the jaw of one of said levers having in its end two slots and a wedge pivoted upon the top of the same, and the jaw of the other of said levers having a flange-shaped end, substantially as described, and 70 for the purposes set forth.

2. In a device for securing hose-bands, the combination of the two bent levers pivoted to each other, the jaw of one of said levers having in its end two slots and a wedge pivoted 75 upon the top of same, the jaw of the other of said levers having a flange-shaped end, and the spiral spring located between said levers, substantially as described and set forth.

In testimony whereof I affix my signature in 80 presence of two witnesses.

CHARLES L. HALSTEAD.

Witnesses:

MARTIN BERGH,
ELLA BRAKKE.
